UNITED STATES PATENT OFFICE.

HERALD P. ARNT AND THOMAS N. AIKENS, OF LAKewood, OHIO.

WHEEL-SPOKE DIE AND METHOD OF ITS USE.

Application filed July 16, 1921. Serial No. 485,354.

To all whom it may concern:

Be it known that we, HERALD P. ARNT and THOMAS N. AIKENS, citizen of the United States of America, and subject of the King of Great Britain, respectively, residing at 1552 Robinwood Avenue and 1564 Wagar Avenue, respectively, city of Lakewood, in the county of Cuyahoga and State of Ohio, have invented a new and useful Improvement in Wheel-Spoke Dies and Methods of Their Use, of which the following is a specification, the principle of the invention being herein explained and the best mode in which we have contemplated applying that principle, so as to distinguish it from other inventions.

Our invention relates to a combined blanking and forming die adapted partially to produce a one-piece tubular wheel spoke, as well as to the method of its operation.

We are well aware, that owing to the growing scarcity and therefore rising cost of wood having the properties which are adapted to withstand the severe stresses to which wheel spokes are subjected, hollow metal spokes have already come into vogue; indeed, we have ourselves been for some time engaged in the manufacture of tubular wheel spokes. We have learned from experience that the trade is strongly inclined to favor and accordingly it is the object of our present invention to manufacture an integral tubular wheel spoke resembling in shape the well known conventional design of wooden spoke.

Adverting to the drawings:

Figure I is a vertical longitudinal section through the middle of our improved die, feasibly mounted on a press, certain parts being shown in elevation.

Fig. II is a plan section taken on line II-II of Fig. I, one half of the die being shown as a plan view, punch not shown.

Fig. III is a section on line III-III of Fig. II.

Fig. IV is a section on line IV-IV of Fig. II.

Fig. V is a section on line V-V of Fig. II.

Fig. VI is a view similar to Fig. V with the die shown open.

Inasmuch as the necessary parts, by means of which our die is suitably mounted and caused to be operated, are with the possible exception of minor details, old and well known to the art, a very cursory description

of the parts of the press will be deemed sufficient.

A bolster plate 1 has over it a bottom shoe 2 and in spaced relation to the latter a top shoe 3, their relative position being determined and controlled by means of guide pins 4 mounted in appropriate bushings 5. The usual stripper plate 6 is positioned just above the space to be occupied by sheet metal and above the blanking die 7 with its shearing edge 8.

It will be apparent from the drawings that the blanking die is duplex sided and inasmuch as its opposed conformation walls are symmetrical only one-half of the blanking die need be described and therefore the singular number will be hereinafter employed. A draw punch or stationary forming die 9 is located within the blanking die 7 and has an upper contour clearly to be seen in Figure I. It is of elongated form and its upper surface includes at one end a flat section 10 sloping upwardly in a direction away from the near end, which surface 10 terminates at a peak 11 which may be considered as a straight crosswise extending line. Thereafter, the top surface of the forming die 9, continuing in a direction toward its opposite end slopes rather abruptly downward toward such other end at 12. In consequence, the peak line 11 makes what may be considered as an upwardly projecting shoulder. The surface 12 is curved and merges with a conical surface 13 of considerable longitudinal extent to constitute the main or middle portion of the spoke. It is to be understood that the employment of a conical surfaced forming die over the extent shown is a mere arbitrary preference as against having this middle portion of it semi-cylindrical. A comparatively short distance from the opposite end of the forming die 9 it is pressed along a curved surface 14 to form an arcuate or semi-circular shoulder 15. The corresponding end of the forming die is of semi-cylindrical form at 16 and with that surface the curved surface 14 merges.

As an aid in distinguishing we have designated as B the sheet steel from which the blanks are to be cut. The operations of the dies shown in this application will leave the blank about half formed. Subsequent operations for finishing the spoke form will be performed by a trimming die and a final forming die to constitute the subject matter

of our separate applications bearing Serial Numbers 485,352 and 485,353 and filed of even date herewith.

A blanking punch 17 having the lateral contour 17^a shown in Fig. II first acts to shear the blank along a line corresponding to the edge 17^a at the shearing edge 8. Continuing downwardly each of the sections of the blanking punch 17 draws the spoke blank down on opposite sides of the forming die as disclosed in Fig. V. In so doing, the inner or nave end of the spoke blank b¹ is bent downwardly away from a line b² which is directly over the peak 11, to be flattened by an inclined punch wall 18 against the surface 10 of the forming die. Simultaneously, a portion b³ is pressed downwardly along a curved line corresponding to the surface 12 of the forming die. During the latter stage of the pressing movement a major middle section b⁴ of the blank is curved about the conical surface 13 and is set by means of a forming punch 19 interposed between the sections of the blanking punch 17 as appears in Fig. III. The outer or felloe end of the spoke blank commencing at b⁵ over the shoulder 15 is pressed along a curve b⁶ against the surface 14 to terminate as a semi-cylindrical surface b⁷ by pressing around the surface 16; the surface 20 of forming punch shown in Fig. IV serving to accomplish this purpose.

The bottoms of the blanking punch 17 engage in the usual way pressure pads 21 which actuate pressure pins 22 which in turn depress a plate 23 against the action of springs 24, these pressure pads serving to iron out the spoke as it is being formed. Operated downwardly through the top shoe 3 by engagement with a suitable stop (not shown) is the ordinary knock-out pin 25

to actuate the forming punch 19 which serves as a knock-out pad, as will be readily understood to release the formed blank.

We claim:—

1. The procedure in the method of making a hollow wheel spoke from sheet metal which consists in first bending opposite ends of a blank downwardly about a line and then forming it to concavo-convex shape in both directions from the plane in which said line lies and so that one end is of progressively reduced dimensions.

2. The procedure in the method of making a hollow wheel spoke from sheet metal which consists in first bending opposite ends of a blank about a straight line extending crosswise of the longitudinal dimension of the blank and then forming it to arcuate form on one side of said line and to angular form on the other side of said line.

3. The procedure in the method of making a hollow wheel spoke from sheet metal which consists in first bending opposite ends of a blank about a straight line extending crosswise of the longitudinal dimension of the blank nearer one of its ends and then forming it to angular form in a direction toward the end nearest said line and to arcuate form on the opposite side of said line.

4. A forming die having a surface at one end flat and having nearer its other end a straight raised line extending across from one side to the other, the other end of said die being of concave form, opposite ends of said die sloping downwardly in directions away from said raised line.

Signed by us, this 5th day of July, 1921.

HERALD P. ARNT.
THOMAS N. AIKENS.
